UNITED STATES PATENT OFFICE.

EARL BARNEY, OF SCHENECTADY, NEW YORK.

THERMOSTAT.

SPECIFICATION forming part of Letters Patent No. 516,043, dated March 6, 1894.

Application filed September 20, 1893. Serial No. 485,948. (No model.)

To all whom it may concern:

Be it known that I, EARL BARNEY, of Schenectady, in the county of Schenectady and State of New York, have invented a new and 5 Improved Thermostat, of which the following is a full, clear, and exact description.

My invention relates to improvements in thermostats, and the object of my invention is to produce an extremely simple apparatus 10 which is especially adapted for use in small places where it is hard to reach and adjust the thermostat, and also to construct the thermostat so that it is very sensitive to changes of temperature, and may be very 15 easily adjusted so as to operate to close an electric circuit at any desired variation of temperature.

My improved thermostat on account of its adjustability and the ease with which it may 20 be adjusted, is especially adapted for use in incubators and similar apparatus, and is intended when the main blade is moved and the temperature changes, to close a circuit through an electric motor, and the latter will 25 do the work required of it in the usual way, the motor connection forming no part of my invention.

To these ends my invention consists of certain features of construction and combinations of parts, as will be hereinafter described 30 and pointed out in the claims.

Reference is to be had to the accompanying drawings forming a part of this specification, in which similar figures and letters of reference indicate corresponding parts in all the 35 views.

Figure 1 is a side elevation of the thermostat with parts in section. Fig. 2 is a plan view of the same; and Fig. 3 is a diagrammatic view showing the manner in which it 40 may be connected with a motor and battery.

The thermostat is provided with a suitable base 10 which is preferably of conducting material and on this is secured a box or bearing 45 11 in which the post 12 is mounted, this post having a reduced lower end 13 which rests in the box and which is fastened therein by a set screw 14. By means of this set screw the blade 15 may be adjusted and held 50 in position. The box 11 is adapted to turn in the base 10 and this enables the post 12 and box 11 to oscillate or swivel slightly when

the blade of the thermostat is moved. The thermostat is provided with a blade 15 which extends horizontally above the base 10 and 55 which, at one end, is secured to the post 12. The thermostat blade is made up of two parts 15^a and 16 of different expansibility, such as iron and brass, for instance, and these parts are riveted firmly together so that when the 60 metals expand, the blade will be turned in one direction, and when they contract the blade will be turned in another direction, this movement being occasioned by the fact that one part expands more rapidly than the 65 other, and consequently, during the expansion, the part which expands less rapidly will have a restraining effect on the other, and cause it to swing to one side. The part 15^a projects at its free end beyond the part 16, 70 and it carries contact pieces 17 which are adapted to touch the contact screws 18 or 18^a, these screws being supported horizontally in posts 19 and 19^a, and the latter are secured in insulating material 20 on the base 10. It 75 will be seen that by adjusting the screws 18 and 18^a, the blade 15 may be made to strike them when moved, to any desired extent. The posts 19 and 19^a are connected by wires 80 a and a' respectively, with binding posts 21 and 21^a which are insulated on the base 10, and a third binding post 22 is secured to the base and a connection is formed between this binding post and the blade 15 through the base, the box 11 and the post 12. 85

The thermostat may be connected with a battery and motor, as shown in Fig. 3. Here the binding posts 21 and 21^a connect with one pole of a battery B by means of wires b and b' while the third binding post 22 connects 90 with the motor 23 and the other pole of the battery by wire c.

It will be seen, that when the blade 15 is swung in one direction, it contacts by means of its buttons 17 with the screw 18 and a circuit is closed, which is as follows: from the battery B through the wire b, the binding post 21, the wire a, the post 19, the contact screw 18, the blade 15, the post 12, the box 11, the base 10, the post 22 and the wire c, 100 through the motor and back to the battery. If, however, the blade 15 swings in the opposite direction it strikes the contact screw 18^a and the circuit is then closed through the

wire b' , the post 21^a, the wire a' , the post 19^a, the screw 18^a, the blade 15, the post 12, the box 11, the base 10, the post 22 and the wire c , back through the motor to the battery. It 5 will thus be seen that the circuit will be closed through the motor when the blade 15 turns in either direction, and it will be understood that the motor may be arranged so as to turn in one direction when one circuit is closed, 10 and the other when the second circuit is closed, and the motor may be made to operate any mechanism such as a damper, in the usual way.

It will be seen that the instrument may 15 be very nicely adjusted by means of the contact screws 18 and 18^a and as the blade 15 is mounted in a revoluble support, the instrument is very sensitive.

Having thus described my invention, what 20 I claim as new, and desire to secure by Letters Patent, is—

1. A thermostat, comprising a conducting base, a box journaled thereon, a post mounted in the box, a blade secured to the post and 25 extending laterally from it, the blade being formed of materials of differing expansibility,

riveted together, posts insulated on the base, contact screws mounted horizontally in the posts and extending opposite the free end of the blade, binding screws insulated on the 30 base and connected with the contact posts, and a third binding post on the base and in electrical contact therewith, substantially as described.

2. A thermostat, comprising a base, a box 35 journaled on the base, a post adjustably mounted in the box, a blade secured to the post and formed of two materials of unequal length and of different expansibility secured together, the longer material being provided with contact pieces, insulated posts on the base, contact screws carried by the posts, insulated binding screws on the base and connected with the contact posts, and a third binding post on the base and electrically connected with the blade, substantially as described. 40 45

EARL BARNEY.
